DUAL OIL BURNER WITH COMMON AIR
AND OIL CONTROL

Joseph A. Logan, Hadley, and Philip H. Bills,
Longmeadow, Mass., assignors to Gilbert &
Barker Manufacturing Company, West Springfield,
Mass., a corporation of Massachusetts

Application February 13, 1948, Serial No. 8,184

5 Claims. (Cl. 158—28)

1

This invention relates to improvements in dual oil burners of the oil pressure atomizing type, which are adapted for firing two separate heating appliances, one a house heating furnace and the other a heater for the household hot water supply system, and which make use of a single power-operated unit for supplying oil and air to both burners.

Various examples of dual burners for the purpose described will be found in the prior art. In some cases, the two burners may be operated alternately or simultaneously while in others alternate operation of the two burners is compelled but in no case, so far as we are aware, can both burners be operated with the same and high efficiency. According to this invention, the two burners must operate alternately.

The object of this invention is to provide in a burner of the type described, improvements, which will enable each heating appliance to be fired with the same and high efficiency so that each burner will work as well as the other.

For the above purpose, it is important that the rates at which air is supplied by the one fan to the two burners be adjustable accurately, the one independently of the other, so that the air may be supplied to each burner at precisely the right rate with respect to the rate of oil flow from such burner to produce the desired high degree of combustion efficiency. With each burner thus arranged to be set for operation at high combustion efficiency, the supply of air and oil may be automatically shifted from one burner to the other for individual operation of the burners so that each may function at the high efficiency, for which it is set, without affecting the other since joint operation of the burners is precluded.

The invention will best be understood from the detailed description of the one example shown in the accompanying drawings, in which:

Figs. 1 and 2 are exterior side elevational and top plan views, respectively, of a dual oil burner embodying the invention;

Fig. 3 is a sectional plan view, taken on the line 3—3 of Fig. 1 and drawn to a larger scale, showing the air valve for connecting one or the other of the air conduits to the outlet of the fan casing;

Fig. 4 is a sectional elevational view of the burner, taken on the line 4—4 of Fig. 2;

Figs. 5 and 6 are sectional plan views taken on the lines 5—5 and 6—6, respectively, of Fig. 4;

Fig. 7 is an end elevational view, partly in section to show the air shutter and mechanism for moving it from one position to another to secure different rates of air flow and the precision ad-

2

justing means for accurately determining said positions;

Fig. 8 is a diagrammatical view of the system for supplying oil to the atomizing nozzles and the hydraulic motors used to operate the air shutter and air valve; and

Fig. 9 is a diagrammatical view showing an electrical system for controlling the burner.

Referring to these drawings: Figs. 1 and 2 show the general arrangement of parts of the dual burner of this invention. This burner includes a single power-operated unit for supplying air and oil for combustion to either of the two burners and thus to either of two combustion zones. This unit is best shown in Fig. 7 and comprises an air supply fan 1 and an oil supply pump 2, both driven by an electric motor 3. As shown, the hub of the fan is fixed directly to the shaft 4 of the motor. The shaft 5 of pump 2 is fixed to the driven element 6 of a centrifugal clutch, the driving element 7 of which is connected by a flexible coupling 8 to the hub of fan 1. The clutch arrangement may be that of Logan Patent No. 1,985,934, granted January 25, 1935, and is arranged to connect the pump 2 to the motor 3 only after the latter and the fan 1 have attained a predetermined high speed and to disconnect the pump from the motor, whenever the speed of the latter and the fan falls below this predetermined speed.

The fan 1 is mounted in a fan casing 9 having an inlet opening 10 (Fig. 7) and an outlet opening 11 (Fig. 4). As shown, this casing is formed in the upper part of a casting 12 which may be suitably supported from the floor as by a pedestal 13. The motor 3 (Fig. 7) is fixed to one side wall of the casing 9 opposite to that wall in which the inlet opening 10 is formed. From this last-named wall extend two parallel arms 14 (Fig. 2), the outer ends of which are integrally connected by a cross bar 15, in which the oil pump 2 is suitably supported, as indicated in Fig. 7. In the lower part of the casting 12 is a cylindrical opening 16 (Fig. 4) into which the fan discharges through its outlet 11. This passage is closed at one end by a cover 17, suitably secured as indicated, to the casting 12. The opposite end of passage 16 communicates with a chamber 18 (Fig. 3), formed within a sheet metal casing 19 of square cross section and secured as indicated to the casting 12. Connected to this casing 19 are two air conduits 20 and 21 which extend to two different combustion zones. As shown in Fig. 1, the conduit 20 leads to, and has its open outlet end communicating

with, the combustion chamber 22 of a warm air furnace, shown in part at 23 and adapted for house heating, and the conduit 21 leads to, and has its outlet end communicating with, a chamber 24 in a hot water heater, shown in part at 25 and adapted to heat a supply of hot water for household use. A pedestal 25' is provided to support the conduit 21.

The one fan 1 may be connected to supply air to either air conduit 20 or 21 by means of an air valve 26 (Fig. 3). A partition 27 extends diagonally across the chamber 18 and has an opening 28 therein. The air valve is suitably fixed to a shaft 29, rotatably mounted near its ends (Fig. 4) in the upper and lower walls of casing 19. The air valve is movable from the position shown in Fig. 3 in which it closes the outlet 30 to air conduit 21 and opens the outlet 28 to conduit 20, to a position, in which it closes the outlet 28 and opens the outlet 30. Thus, either one of the air conduits may be connected to receive air from fan 1.

This air valve is automatically moved from one of the described positions to the other by means of a hydraulic motor. This motor includes a cylinder 31 (Fig. 2), fixed to the upper wall of casing 19, a piston 32 reciprocable in the cylinder, a piston rod 33 and a spring 34, located in the cylinder and encircling the rod 33 and adapted to hold the piston at one end of the cylinder. The outer end of rod 33 is pivotally connected to a gear segment 35, mounted on a stud 36, fixed to the upper wall of casing 19 and meshing with a pinion 37, fixed on the upper end of the shaft 29 of air valve 26. The spring 34 holds this valve in position to close the outlet 30 and thus prevent flow of air from the fan to the air conduit 21, which supplies the hot water heater combustion zone, and open the outlet 28 and connect the fan to the conduit 20, leading to the hot air heating combustion zone. When oil is admitted to the cylinder 31, by means later to be described, the piston 32 will be moved against the force of spring 34 to carry the air valve 26 into position to close the outlet 28 and open the outlet 30, thus allowing fan 1 to supply air to the air conduit 21 which leads to the hot water heating zone.

Located in the air conduits 20 and 21 are oil-atomizing nozzles 38 and 39, respectively, each adapted to supply a spray of finely divided oil particles to be mixed with the air supplied, as above described. Suitable ignition means, such as the pairs of spark electrodes 40 and 41, supplied with high tension current by means to be later described, are provided one pair in each air conduit to ignite the combustible mixture of air and oil. The nozzles 38 and 39 are supplied with oil under proper pressure through oil conduits 42 and 43, respectively, adapted to be connected, by means to be described, one at a time, to the oil pump 2. These nozzles 38 and 39 will, in the usual case, have different firing rates, suitably proportioned for the heating work to be performed. The nozzle 39 will generally have the smaller firing rate. Each nozzle is preferably of the so-called mechanical or oil pressure atomizing type.

In many cases, the hot water heater may be adequately fired at a rate considerably less than one gallon an hour, say for example, one half-gallon an hour. A mechanical atomizing nozzle having an orifice small enough to emit oil at such a low rate under efficient atomizing pressures is easily and frequently clogged. When the

nozzle orifice is made large enough to avoid easy clogging, the low rate of oil emission will not be had unless the pressure is greatly reduced, say to one-quarter of the normally efficient atomizing pressure, with the result that the oil cannot be efficiently atomized and mixed with air by the ordinary method. In such cases, it is preferred to mix the air and oil substantially in the manner disclosed in Logan Patent No. 2,411,048, granted November 12, 1946. A perforated cylinder (Fig. 4) formed in two axially aligned sections 44 and 45, is mounted inside the air conduit 21 near its outer end. For convenience in mounting, the conduit 21 has a separate end section 21' and these parts 21 and 21' have annular flanges 46 and 47, respectively. The sections 44 and 45 of the perforated cylinder also have annular flanges 48 and 49, respectively, which abut and are clamped between the flanges 46 and 47 by a series of screws 50. The perforated cylinder is thus supported from the air conduit 21. The outer end of section 21' is turned to engage the outer periphery of the section 44 of the perforated cylinder, thus forming annular chambers 51 and 52 around the sections 44 and 45, respectively. Air forced by fan 1 into conduit 21 enters chamber 52 and thence passes through openings 54 and 53 in flanges 48 and 49, respectively, into chamber 44. Air from these chambers passes through a multitude of closely spaced perforations 55 in the peripheral wall of the cylinder in many radial jets to mix with the oil spray emitted from nozzle 39. The inner end 56 of the section 45 is of frusto conical form, having a central hollow hub 57, in which the nozzle-bearing end of oil conduit 43 is suitably fixed, as indicated. This frusto-conical part 56 is also provided with many perforations 58, through which air from conduit 21 passes in jets to mix with the oil spray from the nozzle 39. This part 56 has two larger openings through which the spark electrodes 41 extend, terminating in igniting relation to the spray from nozzle 39. These electrodes 41 are supported in insulators 59, mounted in a support 60, fixed to oil conduit 43. Preferably, one of the flanges, as 48, of the perforated cylinder is angularly adjustable relative to the other flange 49 so that the holes 53 may be moved from a position of registration with holes 54 to various other positions in which the holes 53 are to varying degrees out of register with holes 54. In this way, the amount of air passing into the chamber 44 may be varied. As shown in Fig. 5, the flange 48 has a series of slots 61 through which the retaining screws 50 pass, thereby enabling the flange and the section 44 to be turned slightly, when screws 50 are loosened, for the purpose described. The flange 48 may have an outwardly projecting lug 62 for convenience in turning this flange.

For the hot air heating zone, the atomizing nozzle 38 is located near the open outlet end of air conduit 20 and produces a conical spray outside the conduit in the combustion chamber 22 of the warm air furnace 23. The air flowing through conduit 20 is directed into the oil spray by a deflector 63 on the end of the conduit and the mixture is ignited by the spark electrodes 40.

It will be understood that the air may be supplied to and mixed with the oil spray from the nozzle 38 in the same manner that it is supplied to and mixed with the spray from nozzle 39. The latter method may be desirable even though it is not necessary, as it is in the case of a low capacity nozzle, such as the nozzle 39. Also, if

the nozzle 39 has a sufficiently large capacity, such as one gallon per hour or more, then the air may be supplied to and mixed with the oil spray from the nozzle 39 in the same way that it is supplied to and mixed with the oil spray from the nozzle 38.

The ignition electrodes 40 (Fig. 3) are mounted in insulators 64 fixed as indicated to a support 65, in which the outer and nozzle-bearing end of the oil conduit 42 is also fixed. The support 65 (Fig. 4) is suitably fixed as by the screws 66 to conduit 20. The electrodes 40 are connected by wires 67 (Fig. 3) to the high tension terminals 68 of an ignition transformer which is mounted in a case 69, fixed to one side wall of the casting 12. The assembly of nozzle and electrodes may be removed or replaced through an opening in conduit 20, which opening is normally closed by a cover 70, secured as indicated to the conduit. With the cover removed, access is had for the connection or disconnection of the wires 67 and for the connection or disconnection of the oil conduit 42 at the union 71.

The electrodes 41 are supplied with high tension current from a separate transformer mounted in a case 72, fixed to the conduit 21 (see Figs. 4 and 7). The wire connections have not been shown, except diagrammatically in Fig. 9, but they will be similar to those shown for the electrodes 40. An opening, normally closed by a cover 72', is provided in air conduit 21 to permit access for the connection or disconnection of the wires to or from the electrodes and for connection or disconnection of the oil conduit 43 at the union 73. With these wires and the conduit 43 disconnected, the assembly of nozzle 39, electrodes 41 and perforated cylinder 44, 45 may be removed with conduit section 21', when the screws 50 are removed.

The oil supply system is shown in its entirety in a single diagrammatical view in Fig. 8. The various elements of the system, such as the pump, the pressure regulating valves, the firing rate selector valve, and the hydraulic motors, together with the necessary pipe connections, are shown with their mounting and arrangement in relation to the burner, partly in each of Figs. 1, 2, 3, 4 and 7. However, an understanding of the system can be more easily and quickly obtained from the diagrammatical showing of Fig. 8.

The pressure regulating valve for the high rate nozzle 38 is shown as incorporated into the casing of pump 2. A valve 74 is urged by a spring 75 against a valve seat 76 to close off communication between a chamber 77, which is connected by means not shown to the outlet of the pump, and an outlet pipe 78. When the pressure in chamber 77 rises to a predetermined value, say 85 pounds per square inch, valve 74 will open and allow oil to pass into an outlet pipe 78. When the oil in such chamber reaches a somewhat higher pressure, say 100 pounds per square inch, valve 74 will be moved to the left far enough to uncover a port 80 and allow oil from chamber 77 to flow through this port into a chamber 81 which is connected to the suction side of pump 2. The pressure at which valve 74 opens may be varied by turning a screw 75'. An example of a pump having a pressure regulating valve such as described will be found in Wahlmark Patent No. 2,232,983, dated February 25, 1941, to which reference is made for a complete disclosure of the pump and valve construction if such is necessary or desired.

The outlet pipe 78 conducts the oil to a firing rate selector valve, mounted in a casing 83, and such valve directs the oil to one or the other of the two oil conduits 42 and 43. The casing 83 is of magnetic material and has outlets 84 and 85, at opposite ends thereof, both leading from a central space within a sleeve 86 of non-magnetic material. The pipe 78 delivers oil into this space. Within the sleeve 86 is a slideable valve 87 of magnetic material and a spring 88 which tends to hold valve 87 in position to close the outlet 85 and open the outlet 84. Surrounding the sleeve 86 is a solenoid 89 which, when energized, will move valve 87 against its spring into position to open the outlet 85 and close the outlet 84. This valve has been shown only diagrammatically. It is a standard three-way solenoid valve obtainable in the open market and the details of its construction are unnecessary to an understanding of this invention. The outlet 84 is connected to the oil conduit 42 which supplies the high rate nozzle 38. The outlet 85 is connected by a pipe 90 which connects, as will later appear, with the other oil conduit 43 which supplies the low rate nozzle 39. Thus, when the solenoid 89 is de-energized, the pump 2 will supply oil to the high rate nozzle 38 and, when the solenoid is energized, the pump will supply oil to the low rate nozzle 39.

When the hot water heater is to be fired at a low rate, such as one-half gallon per hour and such as to make desirable the use of the perforated screen combustion chamber, above referred to, it will be necessary to have the oil supplied to nozzle 39 at a rate substantially less than that at which it is supplied to nozzle 38. In such case, a second pressure regulating valve in a casing 91 is provided. Within this casing, is a cylinder in which a piston 92 is slidably mounted. The piston carries a valve 93 which controls the outlet to oil conduit 43. A spring 94, acting between the piston and a seat on a screw 95, threaded into casing 91, tends to hold the valve in closed position. When valve 87 opens outlet 85, oil at high pressure from pump 2 enters the cylinder through pipe 90 on the side of piston 92 opposite from spring 94 and moves the piston against its spring to open valve 93. The space on the other side of the piston is connected by a pipe 96 to the suction side of pump 2, as to the suction pipe 97. Shortly after valve 93 opens, the piston 92 will move far enough to connect the space on the valve side of the piston to a groove 98 in the cylinder wall, which groove leads to the space on the other side of the piston, whereby oil may by-pass through pipe 96 to the suction side of the pump and reduce the pressure of the oil supplied to nozzle 39. The movement of piston 92 will continue until the pressure of the oil acting on piston 92 is balanced by the pressure of spring 94, whereupon the oil fed to nozzle 39 will be at the predetermined pressure. Such pressure is of course, variable by adjusting screw 95. This pressure regulating valve is in this instance a reducing valve. The piston 92 is provided with an opening 99 therethrough of small cross section, affording a constant but restricted by-pass. This by-pass 99 enables venting of the cylinder 31, described before, and the cylinder of another hydraulic motor, to be later described, after valve 87 has closed the outlet 85 to cut off flow of oil to casing 91 and after the subsequent closing of cut-off valve 92. The pressure in the cylinders of the hydraulic motors will be reduced to sub-atmospheric to enable the pistons of both motors to be

moved back by their respective springs and to assist in such movement of the pistons.

The nozzles 38 and 39, in some cases, may have different rates and still operate at the same pressure, the rate being determined by the size of the nozzle orifice. Under these conditions, the second pressure-regulating valve will not be necessary. The pipe 90 would be connected at all times to pipe 43 without any valve, such as 93. Also, the pipe 90 would remain connected to pipe 120 and the constant but restricted passage 99 would be retained to vent the cylinders of the two hydraulic motors, or other means could be provided for the purpose.

The rate at which air is supplied by fan 1 to the conduit 20 has to be different from that at which air is supplied to conduit 21 to provide for efficient combustion, when the nozzles 38 and 39 have different firing rates. The rate of air supply is controlled by an air shutter 100 (Fig. 7), which is here shown as associated with the inlet opening 10 of the fan casing 9 although it might equally well be associated with the outlet of the fan. As shown, this shutter is of annular form, encircling the driven element 6 of the clutch and being movable axially toward and away from the inlet opening 10 to vary the rate of air flow into the fan casing 9. This shutter has fixed thereto a nut 101 into which is screwed a threaded rod 102. This rod has near its ends plain cylindrical portions, which are mounted in bearings 103 and 104, respectively formed in one side wall of fan casing 9 and in the cross bar 15. The rod is rotatable and axially movable in these bearings. Fixed to rod 102, intermediate its ends, is a clutch collar 105 by means of which the rod and the shutter may be moved axially from one predetermined position, such as that shown, in which the shutter is set for the higher rate of air flow necessary for conduit 20, to another predetermined position, in which the shutter is set for the lower rate of air flow for conduit 21. The axial movement of rod 102 is limited by suitable stops, which determine the aforesaid predetermined positions. The high rate position is determined by the inner end of a screw 106, which is threaded into the end wall of a sheet metal casing 107 and which is adapted to be engaged by clutch collar 105. This casing is fixed at one end to the cross bar 15 and at the other end to fan casing 9. It encloses the shutter 100, clutch elements 6 and 7, and the driving connections, except for air inlet openings 108 of ample aggregate area. The high rate position of the shutter 100 may be adjusted with precision by turning screw 106. On rod 102 is a shoulder 109, which when the rod 102 is bodily moved to the right, engages with the end face of bearing 103 to determine the low rate position of the shutter. This low rate position may be adjusted with precision by rotating screw 102 and causing the shutter to move toward or away from opening 10 to the desired degree.

For automatically moving the shutter between its two predetermined positions, a hydraulic motor is provided. This motor includes a cylinder 110 formed by a bore in a block 111, secured by screws 112 (Fig. 3) to the wall of the passage 16 in casting 12, and a piston 113 and piston rod 114. This block 111 also serves to support the firing rate selector valve, its casing 83 being mounted in a hole in the block, as shown in Fig. 1. The outer end of cylinder 110 (Fig. 7) is closed by an annular plug 115 threaded into the cylinder. A spring 116, encircling the piston rod 114, acts between the plug 115 and piston 113

with a tendency to hold the piston in its extreme inner position. The outer end of the piston rod 114 is pivotally connected to the lower end of a lever 117, which is fulcrumed on a pin 118, fixed in block 111, and extends upwardly into the casing 107 and has its upper end engaged in the groove in the clutch collar 105. The spring 116 tends to hold the shutter 100 in the high rate position illustrated. Oil under pressure may be admitted by means of a pipe 119 (Figs. 1, 3 and 8), connected with pipe 90, to the inner end of cylinder 110 to move piston 113 outwardly against spring 116 thus swinging lever 117 clockwise, as viewed in Fig. 7, to move clutch collar 105 and the attached rod 102 to carry the shutter 100 into its other and low rate position. Thus, whenever oil is admitted by the firing rate selector valve 87, on energization of solenoid 89, to the low rate nozzle 39, oil is also admitted to the hydraulic motor which shifts the air shutter 100 into position for operation at the low firing rate.

The other hydraulic motor 31 for operating the air valve 26 is also connected to receive oil at the same time as the low rate nozzle 39. This is effected by a pipe 120 (Fig. 8) which connects the cylinder of such motor to the cylinder in the valve casing 91 on the same side of piston 92 as that to which pipe 90 is connected.

The motor 3, which drives the one air and oil supply unit for the two burners, is adapted to be started and stopped under the control of a room thermostat switch, which closes on a demand for heat from the hot air furnace and opens when such demand is satisfied, or under the control of an aquastat switch, which closes on a demand for heat from the hot water heater and opens when such demand is satisfied. The solenoid 89, which controls the oil valve 87, and indirectly the air shutter 100 and air valve 26, is arranged to be energized only when the aquastat switch is closed to start the motor. Then, the oil valve 87 is positioned to direct oil to nozzle 39; the air valve 26 is positioned to direct air to air conduit 21; and the shutter 100 is positioned for the low rate of air flow. When the room thermostat switch closes to start the motor, the solenoid 89 is not energized and the oil valve 87 is positioned to direct oil to the high rate nozzle 38; the air valve 26 is positioned to direct air to air conduit 20 and the shutter 100 is positioned to provide the high rate of air flow.

An electrical control system for effecting the described results is shown schematically in Fig. 9. The motor 3 is controlled by a switch 121 in a circuit comprising the 120 volt supply wires 122 and 123 and a wire 124. One ignition transformer, the secondary 125 of which is connected by the wires 67 to the ignition electrodes 40, has its primary 126 connected by wires 127 and 128 to the wires 123 and 124 and thus in parallel with motor 3. The other ignition transformer, the secondary 129 of which is connected to the electrodes 41 by wires 130, has its primary 131 connected by wires 132 and 133 to wires 127 and 128, respectively, and thus in parallel with the other primary 126 and motor 3. Thus, on closure of switch 121, the motor 3 will be started and the primaries 126 and 131 of both ignition transformers will be energized. The solenoid 89 is also connected in parallel with the motor 3 in a circuit which includes the motor switch 121 and a second control switch 134. This circuit may be traced as follows, from supply wire 122, closed switch 121, wire 124 to a wire 135, wire 75 135, closed switch 134, wire 136, solenoid 89, wire

137 to wire 127, to the left along wire 127 to supply wire 123, and wire 123.

The switch 121 is actuated by a relay, the coil of which is marked 138. This coil can be connected to one or the other of two low voltage energizing circuits, both supplied from the secondary 139 of a transformer, the primary 140 of which is connected by wires 141 and 142 to the supply wires 122 and 123, respectively. One of these energizing circuits is controlled by an aquastat switch 143, adapted to be actuated by a thermostatic element 144, responsive to the temperature of the water in the hot water heater, closing when the temperature of such water falls below a predetermined value and opening when the temperature of such water rises above a predetermined value. This circuit, controlled by aquastat switch 143, may be traced as follows, from the right hand terminal of secondary 139 by wires 145, 146 and 147 to one terminal of switch 143 and from the other terminal of the latter by a wire 148 to a contact 149, a switch 150, which presently engages contact 149, wire 151, coil 138 and wires 152 and 153 to the left hand terminal of secondary 139. Thus, when the aquastat switch closes, coil 138 will be energized to close switch 121 and thus start the motor 3, and energize both ignition transformers and the solenoid 89. When the hot water heating burner has operated long enough to satisfy the demand, switch 143 will open and break the circuit to relay coil 138 causing switch 121 to open and stop the motor 3 and de-energize the two ignition transformers and the solenoid 89.

The other energizing circuit for relay coil 138 includes the described switch 150, a second contact 154 for the latter and a wire 155 connecting contact 154 to wire 145. This circuit may be traced as follows, from the right hand terminal of secondary 139, by wires 145 and 155, contact 154, switch 150, which is assumed to be engaged with contact 154, wire 151, relay coil 138 and wires 152 and 153 to the left hand terminal of secondary 139. This switch 150 is actuated by a relay, the coil of which is marked 156. This coil is adapted to be energized by a circuit which is controlled by a room thermostat switch 157, which is responsive to the temperature of the rooms to be heated by the warm air furnace heated by the flame from nozzle 38, closing and opening accordingly as the temperature in such rooms is respectively below or above a predetermined temperature. When the room thermostat switch 157 closes, a circuit is closed to relay coil 156 as follows, from the right hand terminal of secondary 139, by wires 145, 146 and 158, switch 157, wire 159, relay coil 156 and wire 153 to the left hand terminal of secondary 139. Thus, switch 150 will be moved to engage contact 154 and close the second described energizing circuit to the relay coil 138. At the same time, switch 150 will be disengaged from contact 149 to break the first described and aquastat-controlled energizing circuit to the relay coil 138. The relay coil 156 also controls the control switch 134 for solenoid 89, opening and closing such switch accordingly as the relay coil 156 is respectively energized or de-energized. Thus, when the room thermostat switch 157 closes on a demand for heat from the warm air furnace, fired by the nozzle 38, the solenoid 89 will be de-energized, allowing the oil valve to close the conduit 43 leading to nozzle 39 and open the conduit 42 leading to nozzle 38. At the same time, the air shutter 100 and air valve 26 will be moved

back into their illustrated positions to respectively provide for high rate air flow and the connection of the outlet of fan 1 to the air conduit 20 leading to the combustion chamber of the warm air furnace.

It will be clear that the room thermostat switch 157 will take precedence over the aquastat switch 143 because of the switch 150 which opens the aquastat-controlled energizing circuit to the relay coil 138, whenever the room thermostat controlled energizing circuit for relay coil 138 is closed. Thus, if the aquastat switch is closed so that the nozzle 39 is firing the hot water heater and a demand occurs for heat from the warm air furnace, the room thermostat switch will take the control of relay 138 away from the aquastat switch and also cause de-energization of solenoid 89 to shift the air and oil supply to the warm air furnace and increase the rate of air supply proportionately to the rate at which oil is supplied to nozzle 38. Also, if the nozzle 38 is firing the warm air furnace, the aquastat switch cannot cause operation of nozzle 39 to fire the hot water heater.

It will be understood that the control system described may be used with all the customary safety devices. No attempt has been made to complicate the present disclosure by the illustration and description of any of these devices. Such devices are old and well known in the art and an understanding of them is not necessary to an understanding of the invention.

The invention is also independent of the control system used and may in fact be used without one. It will be obvious that the valve 87 could be actuated by manual control and, when so actuated, the various functions described will be accomplished in the same way. The automatic control has been described as being desirable but it is not indispensable to the invention.

The invention provides for the supply of air and oil from one supply source to either of two burners but not to both burners at the same time. The alternate operation of the burners enables the oil and air to be supplied to each under exactly the right conditions to effect the desired high efficiency of oil burning at each heating appliance. The valve 74 can be accurately regulated by the screw 75 to secure just the right pressure of the oil fed to the high rate nozzle 38 to deliver from the latter atomized oil at the desired rate to properly fire the warm air furnace. Then, when the valve 87 is moved by energization of solenoid 89, the oil pressure is reduced by valve 93 to the proper, and usually much lower, pressure necessary for the nozzle 39 to deliver atomized oil at the desired rate to properly fire the hot water heater. The valve 93 can be regulated, accurately and with precision, wholly independently of the other regulating valve 74, by means of screw 95. Each oil pressure may be determined with close accuracy and an automatic shift from one pressure to another will be effected coincidentally with the shifting of the oil from one burner to another by the operation of valve 87. And the air supply may also be regulated with accuracy and precision, the single shutter 100 serving to control the air supply for both burners. This shutter may be set with accuracy in one predetermined position, in which the rate of air flow is correct for the rate of oil emitted from nozzle 38 to fire the warm air furnace. Such position is that illustrated, where the collar 105, which moves with the shutter, abuts the stop 106. The latter is a screw which

affords the means for a precision adjustment of said predetermined position. The shutter 100 may also be set with accuracy in another predetermined position, in which the rate of air flow is correct for the rate of oil emitted from nozzle 39 to fire the hot water heater. This second predetermined position is determined by the stop, which in this case consists of the end face of bearing 103. The shutter-supporting threaded rod 102, being rotatable in the shutter nut 101, provides the means for a precision adjustment of the second predetermined position by moving the abutment 109 on the threaded rod relatively to the fixed stop 103. Then, the hydraulic motor 110—113 provides for automatically shifting the shutter from one of said predetermined positions to the other. This motor and the hydraulic motor, which shifts the air valve 26, are interlocked with the oil valve 87 because when oil under pressure from the pump is directed by this oil valve to the low rate nozzle 39, some of this oil is simultaneously fed to both motors to shift the air valve 26 to connect air conduit 21 to the outlet of fan 1 and to shift shutter 100 into its low rate position. When the oil valve is turned to cut off oil supply to nozzle 39, both motors are simultaneously connected to the suction side of the pump and their springs come into action, in one case to shift air valve 26 to connect conduit 20 to the fan outlet and in the other case to shift the shutter to its high rate position.

The invention thus provides a dual oil burner of the oil pressure atomizing type for use in alternately firing a warm air furnace for room heating and a heater for the household hot water system, characterized in that the one power-operated oil and air supply unit may supply the oil and air at different rates, each closely regulable independently of the other, to the different burners so that each heating appliance may be fired with equal and high efficiency.

We claim:

1. A dual oil burner, comprising, a fan casing having inlet and outlet openings, two air conduits connected to the casing to receive air from the outlet opening, an air valve movable from one position to another to connect one or the other of said conduits to receive air from the fan casing and operable when connecting either one of the conduits to disconnect the other, a fan in said casing, a motor for driving the fan, an adjustable shutter to control one of said openings in the fan casing and determine the rate at which air is supplied by said fan, said shutter being mounted for movement toward and away from said one opening, stationarily-supported stops for limiting the movement of the shutter in both directions to one or the other of two predetermined positions, an oil pump driven by said motor, two oil conduits and an oil valve for connecting one or the other of them at one end to the pump, said oil conduits extending one into one air conduit and the other into the other air conduit, oil-atomizing nozzles one on the other end of each oil conduit, and means for moving said air valve and shutter, operatively interlocked with said oil valve so that the fan will be connected to supply air to one air conduit when the pump is connected to supply oil to the oil conduit and nozzle in such air conduit and the shutter will be moved into that predetermined position which will determine the proper rate of air flow for such air conduit.

2. A dual oil burner, comprising, a fan casing having inlet and outlet openings, two air con-

duits connected to the casing to receive air from the outlet opening, an air valve movable from one position to another to connect one or the other of said conduits to receive air from the fan casing and operable when connecting either one of the conduits to disconnect the other, a fan in said casing, a motor for driving the fan, an adjustable shutter to control one of said openings in the fan casing and determine the rate at which air is supplied by said fan, said shutter being mounted for movement toward and away from said one opening, stationarily-supported stops for limiting the movement of the shutter in both directions to one or the other of two predetermined positions, precision adjusting means for moving the shutter and stops the one relatively to the other to accurately determine each of said predetermined positions, an oil pump driven by said motor, two oil conduits, and an oil valve for connecting one or the other of them at one end to the pump, said oil conduits extending one into one air conduit and the other into the other air conduit, oil-atomizing nozzles one on the other end of each oil conduit, and means for moving said air valve and shutter, operatively interlocked with said oil valve so that the fan will be connected to supply air to one air conduit when the pump is connected to supply oil to the oil conduit and nozzle in such air conduit and the shutter will be moved into that predetermined position which will determine the proper rate of air flow for such air conduit.

3. A dual oil burner, comprising, a fan casing having inlet and outlet openings, two air conduits connected to the casing to receive air from the outlet opening, an air valve movable from one position to another to connect one or the other of said conduits to receive air from the fan casing and operable when connecting either one of the conduits to disconnect the other, a fan in said casing, a motor for driving the fan, an adjustable shutter to control one of said openings in the fan casing and determine the rate at which air is supplied by said fan, said shutter being mounted for movement toward and away from said one opening, stationarily-supported stops for limiting the movement of the shutter in both directions to one or the other of two predetermined positions, an oil pump driven by said motor, two oil conduits, and an oil valve for connecting one or the other of them at one end to the pump, said oil conduits extending one into one air conduit and the other into the other air conduit, oil-atomizing nozzles one on the other end of each oil conduit, hydraulic motor means operatively connected to the air valve and shutter for moving them from one position to the other, and an oil conduit from said means to said pump and controlled by said oil valve to admit oil from said pump to the motor means to move the air valve to connect one air conduit to the fan when the oil valve connects the oil conduit in such air conduit to the pump and to move the shutter into that predetermined position which will determine the proper rate of air flow for such air conduit.

4. A dual oil burner, comprising, a motor driven pump and fan for respectively supplying oil and air for combustion, said fan having a casing with inlet and outlet openings, first and second air conduits connected to the casing to receive air from the outlet opening, an air valve for connecting one or the other of said air conduits to receive air from said fan, first and second oil conduits extending at one end into the first and

second air conduits respectively, first and second oil-atomizing nozzles connected to said ends of the first and second oil conduits respectively and having different firing rates, a valve for connecting one or the other of said oil conduits to said pump, an adjustable shutter to control one of said openings in the fan casing, and movable between first and second predetermined positions to respectively determine the proper rate of air flow for the first and second air conduits, stationarily mounted stops for limiting the movement of the shutter in both directions to one or the other of said positions, precision adjusting means for relatively moving the stops and shutter to accurately determine said predetermined positions, hydraulic motor means operatively connected to said air valve and shutter and operable when supplied with liquid under pressure to move them in one direction, said motor means including yieldable means for moving said air valve and shutter in the other direction and holding the air valve positioned to connect the fan to the first air conduit and the shutter in said first position, yieldable means for holding the oil valve positioned to connect the first oil conduit to said pump, and a conduit connection between said motor means and pump controlled by the oil valve and closed when the latter is positioned to connect the first oil conduit to the pump, said valve when positioned to connect the second oil conduit to the pump also operable to connect the oil conduit of said motor means to said pump to admit oil under pressure thereto and move the air valve and shutter against said yieldable means to carry the air valve into position to connect the second air conduit to the fan and move the shutter into its second predetermined position.

5. A dual oil burner, comprising, a fan casing having inlet and outlet openings, two air conduits connected to the casing to receive air from the outlet opening, an air valve movable from one position to another to connect one or the other of said conduits to receive air from the fan casing and operable when connecting either one of the conduits to disconnect the other, a fan in said casing, a motor for driving the fan, an adjustable shutter to control one of said openings

in the fan casing and determine the rate at which air is supplied by said fan, said shutter being mounted for movement toward and away from said one opening, stationarily-supported stops for limiting the movement of the shutter in both directions to one or the other of two predetermined positions, precision adjusting means for moving the shutter and stops the one relatively to the other to accurately determine each of said predetermined positions, an oil pump driven by said motor, two oil conduits, and an oil valve for connecting one or the other of them at one end to the pump, said oil conduits extending one into one air conduit and the other into the other air conduit, oil-atomizing nozzles one on the other end of each oil conduit, independently-adjustable pressure-regulating valves one to determine the pressure of oil fed to one oil conduit and one for determining the pressure of oil fed to the other oil conduit, and means for moving said air valve and shutter, operatively interlocked with said oil valve so that the fan will be connected to supply air to one air conduit when the pump is connected to supply oil to the oil conduit and nozzle in such air conduit and the shutter will be moved into that predetermined position which will determine the proper rate of air flow for such air conduit.
